Application July 16, 1945, Serial No. 605,409

9 Claims. (Cl. 93—37)

1

This invention relates to cell case machines and the object is to provide an improved machine for assembling in lattice form slotted partition strips to form an inset for a container which will divide it into compartments for reception of individual bottles, etc. Such inserts or cells characteristically consist of a number of parallel strips slotted part-way through from one edge which are interlocked in a halving joint with relatively perpendicular strips slotted from the opposite edge. It will be convenient to term one set of strips "longitudinals" and the others "transversals," although the distinction is arbitrary. While not limited thereto, my machine is particularly adapted to handle preformed partition strips cut from relatively rigid and thick material, such as faced corrugated board. The assembly of such strips has hitherto remained a hand operation.

It has been proposed to assemble successive transversal strips with successive sets of aligned slots in a rank of longitudinal strips by driving the former one by one by means of a reciprocating ram or plunger into interlocking relation with the latter. In my invention I utilize such a ram having operating means effective to cause it to move through a single inserting stroke and a retreating stroke and govern such means through the slots themselves of the longitudinals so that the plunger is actuated when and only when the slots are in proper position to receive the transversal. This may be effected by directing a flow of energy, in the example about to be specifically described luminous energy, transversely to the longitudinals in the zone of the slots, which flow of energy will be interrupted by the portions of the strips between the slots but on transit of a slot will be released for passage therethrough to initiate an inserting operation.

My invention will be well understood by reference to the following description taken in connection with the accompanying drawings wherein an illustrative embodiment thereof is shown and wherein—

Fig. 1 is an isometric view of the machine as seen from the feeding-in end;

Fig. 2 is a longitudinal section thereof;

Fig. 3 is a similar section on an enlarged scale with parts omitted and illustrates more particularly the feed of the successive longitudinal strips;

Figs. 4 and 5 are fragmentary views on an enlarged scale showing certain details of the transversal-inserting mechanism; and

Fig. 6 is a wiring diagram.

2

Referring to the drawings, the machine there shown comprises a table 10 on which are arranged pairs of spaced plates 12 forming guideways for slidably receiving longitudinal strips, and holding them vertical with the slots upward and spaced in a rank. I use the word "rank" here as in the expression "rank and file" to denote a number of strips side by side and properly spaced in accordance with the spacing which they will have in the finished article. At the output end of the guideways formed by the plates 12 there is provided a ram or plunger 14 reciprocating on vertical guides 16 carried by frame 18, the ram being arranged at the delivery end of a holder for a stack of transversals, the holder having an inclined bottom 20 on which the transversals rest at right angles to the guideways 12 and with their slots down. As best seen in Fig. 4, when the ram 14 is raised, the foremost element 10 of the stack moves forward by gravity past the edge of the bottom 20 against stop strips 22 and is held suspended by the pressure of the stack under the ram to be driven downwardly thereby when it descends, sliding along the forwardly presented sides of the strips 22.

The ram is herein shown as operated by a motor solenoid 24 suspended on a frame 26, the core of the solenoid being connected by a link 28 to a lever 30 pivoted on a bracket 32 projecting from a cross-member of the frame 26. The other end of the lever is connected by link 34 to arm 36 projecting upwardly from the ram 14 and herein shown as guided at its upper end in the tubular guide 38. It will be apparent, particularly from Fig. 2, that when the core of the solenoid is drawn upwardly on energization of the same, it will depress the ram 14 which is returned by the spring 40 connected to lever 30.

To control the ram a light source 42 is provided at one side of the table adjacent the path of the ram and at an elevation corresponding to the path of the slots in the longitudinals. Light therefrom is directed across the table toward a photo-electric cell 44 which, when the light falls thereon, energizes a switch mechanism 46 of well known type, closing it against the action of a spring and energizing the solenoid. This may be effected through a relay mechanism 48 illustrated in the wiring diagram (Fig. 6) but which I do not here describe in detail as it may be of any desired character and its specific nature constitutes no part of the present invention.

Let us suppose that a rank of longitudinals is advanced in proper alignment to the arm. The

portions between the slots shut off the ray of light from the cell. As they come to proper position relative to the ram, the slots move in front of the light permitting the passage of the light ray therethrough which falls on the photo-electric cell and causes operation of the ram. The transverse strip which it inserts in the slots interrupts the ray of light, the switch opens, and spring 40 retracts the ram.

To feed the longitudinals through the machine I may provide at the intake end of the machine, as seen in Figs. 1, 2 and 3, a belt 50 driven through pulley 51, the upper run of the belt being in the plane of the top of table 10. The belt has pusher bars 52 thereon at intervals greater than the length of the longitudinal strips which are to be handled. The guideways formed by the plates 12 extend over the belt and are suitably cut away, as best seen in Fig. 2, to pass the pusher bars.

The longitudinal strips may be fed into the guideways from above at the intake end of the machine to come to rest on the surface of the belt 50 in the path of the pusher bars 52. To simplify the disclosure I have shown no mechanical means for feeding longitudinals and we may assume that they are placed in position by hand.

The operation of the feed may be best understood from Fig. 3. At the left we see a strip *a* engaged by a pusher bar. The rear edges of this and similar strips in the parallel guideways will be engaged by the pusher bar and aligned thereby. As the belt moves, the aligned strips will be advanced to the position of the strip *b* with their centers of gravity beyond the edge of the table 10 to the right of the belt and will push before them in the guideways any preceding strips *c*, the ends of those strips which are on the table to the right of the belt abutting in the operation of the machine. When a strip has reached the position shown at *b*, the pusher bar shown at the right in Fig. 3 will leave the same and the strips *b* and *c* will stop moving, but this is not material because the strips themselves control the inserting mechanism. The pusher at the left will now move into position to engage a set of strips in position *a*, align them and advance them onto the table, pushing before them the preceding strips which are in positions *b* and *c* by abutting contact of the ends of the strips.

As is plain from Fig. 3, the distance between the last slot in one strip, as *c*, and the first slot in the following strip, as *b*, is twice the distance between the slots in an individual strip. Thus the inserting operations do not recur regularly when we consider a series of consecutive longitudinals. However, light does not pass when the abutting ends of the strips pass the ram. The latter is therefore not operated but is actuated solely when the slots are properly positioned and independently of their relative positions or of the speed of movement of the strips.

The assembled cell cases are pushed out from the assembling zone to the right of the table, viewing Fig. 2, and taken away in any desired manner.

Herein the light source 42 and the cell 44 are at opposite sides of the entire rank of longitudinals and the ray passes from one to another through the aligned slots of the entire rank. Thus if one of the longitudinals is misformed and has no slot or a misplaced slot, the inserting mechanism will not be operated and the machine will not jam. The longitudinals in question will pass beyond the inserting point and the resultant

defective cell case will be exposed for inspection and rejection.

I am aware that the invention may be embodied in other specific forms without departing from the spirit or essential attributes thereof, and I therefore desire the present embodiment to be considered in all respects as illustrative and not restrictive; as is in fact clear in several matters from the description itself. Reference is to be had to the appended claims to indicate those principles of the invention exemplified by the particular embodiment described and which I desire to secure by Letters Patent.

I claim:

1. Apparatus for assembling slotted partition strips comprising means for advancing a rank of longitudinal strips past an assembly point, means for inserting a transverse strip in the aligned slots of the rank of longitudinals presented at said point, a device tending to cause a flow of energy across the path of the slotted portion of said longitudinals which is interrupted by the portions thereof between the slots, and means responsive to said flow of energy when released by transit of a slot past said device for causing an operation of said inserting means.

2. Apparatus for assembling slotted partition strips comprising means for advancing a rank of longitudinal strips past an assembly point, means for inserting a transverse strip in the aligned slots of the rank of longitudinals presented at said point, a device to direct a ray of light across the path of the slotted portions of said longitudinals, which ray is interrupted by the portions between the slots, and photo-electric means responsive to the incidence of said ray when released by transit of a slot past said device for causing an operation of said inserting means.

3. Apparatus for assembling slotted partition strips comprising means for advancing a rank of longitudinal strips past an assembly point, means for inserting a transverse strip in the aligned slots of the rank of longitudinals presented at said point and means governed by the arrival of such slots adjacent said point for causing an operation of said inserting means.

4. Apparatus for assembling slotted partition strips comprising means for supporting longitudinal strips on edge, means for supporting a group of cross-strips, means for effecting a relative movement of the longitudinal strips and the group of cross-strips in a direction lengthwise of said longitudinal strips, a motor, means actuated thereby for assembling the cross strips singly and in succession with the longitudinal strips during said movement, and means responsive to the transit past the same of slots in the longitudinal strips for causing the said motor to operate.

5. Apparatus for assembling slotted partition strips comprising means for advancing a rank of longitudinal strips past an assembly point, means for inserting a transverse strip in the aligned slots of the rank of longitudinals presented at said point, and means presented to the side of a longitudinal along the slotted zone thereof and operated by the transit of a slot past the same for causing an operation of said inserting means.

6. Apparatus for assembling partition strips including longitudinal strips and cross-strips, said longitudinal strips having slots at intervals along their length for receiving the cross-strips, a motor, means operated thereby for assembling the cross-strips singly and in succession with the lon-

5
gitudinal strips, a device positioned and arranged to be masked by said longitudinal strips and unmasked intermittently by the slots in the strips during the assembling operation, and control means operated by the unmasking of said device for effecting intermittent, periodic operation of the motor.

7. Apparatus for assembling slotted partition strips comprising means for advancing a rank of longitudinal strips past an assembly point, an inserting device, means to supply successive transverse strips to the device between operations thereof, means for actuating said device through an inserting stroke and a retreating stroke, and means presented to a longitudinal along the slotted zone thereof and operated by the transit of a slot past the same to initiate an operation of said inserting means.

8. Apparatus for assembling slotted partitions comprising means for advancing successive ranks of longitudinal strips as an uninterrupted line past an assembly point, an inserting device, means to supply successive transverse strips to the device, means for effecting single actuations of said device, and means responsive to the transit

10

20

25

past the same of a slot of a longitudinal to initiate an operation of said inserting means.

9. Apparatus for assembling slotted partition strips comprising a support over which a rank of longitudinal strips may move past an assembling point, feeding means, to which successive ranks may be supplied, for advancing the ranks on to the support for continued movement therewith by the thrust of a succeeding rank, an inserting device, means to supply successive transverse strips to said device, and means for effecting an actuation of said device on the arrival of a slot adjacent the assembling point to cause insertion of a transverse strip therein.
